UNITED STATES PATENT OFFICE.

JERROLD GAY BELCHER, OF COLUMBUS, OHIO.

DESIGN FOR AN AMULET OR SIMILAR ARTICLE.

Application filed May 17, 1924. Serial No. 9,637. Term of patent 3½ years.

To all whom it may concern:

Be it known that I, JERROLD GAY BELCHER, a citizen of the United States, and resident of Columbus, in the county of Franklin and State of Ohio, whose post-office address is 213 Arcade Building, Columbus, Ohio, have invented a new, original, and ornamental Design for Amulets or Similar Articles, of which the following is a specification, reference being had to the accompanying drawing, forming part thereof.

Figures 1 and 2 are, respectively, front and side views of an amulet showing my new design.

I claim:

The ornamental design for an amulet or similar article as shown.

In witness whereof, I hereunto subscribe my name this 17th day of April, 1924.

JERROLD GAY BELCHER.
